UNITED STATES PATENT OFFICE.

JOSEF PROKOP, OF PARDUBICE, CZECHOSLOVAKIA.

FEEDING AND DISCHARGING APPARATUS FOR MACHINES FOR MATERIAL TREATMENT.

Application filed April 3, 1925, Serial No. 20,496, and in Czechoslovakia April 17, 1924.

This invention relates to machines for shelling grain, and other material treatment.

According to the present invention a machine of this type is provided having an arrangement which carries out the dual operation of feeding and expelling the material into and out of the machine with the smallest possible disturbance to the speed thereof. The arrangement consists of cams 5 carried on a shaft connected by a dual coupling with a driving shaft, the rotation of the shaft carrying the cams causing the periodical outlet and inlet of the material out of and into a shelling drum. The dual 10 coupling between the driving and cam shafts is actuated by a stop-disc which is adapted by suitable transmission gear to rotate slowly in one direction and quickly in the opposite direction under the action of a spring 15 through an angle less than 360° between two buffers or stops, which are movable away from or towards each other so that the period in which the material is allowed out of and into the machine can be made 20 longer or shorter.

One constructional form of the invention is illustrated by way of example on the accompanying drawings in which:

Fig. 1 is an elevation of the shelling machine;

Fig. 2 is a sectional view illustrating the arrangement of part of the gearing;

Fig. 3 is an enlarged view of a detail;

Fig. 4 is a modification of the stop disc 35 apparatus.

Referring to the drawings:

The stop disc 1 which oscillates on the axle 2 through an angle less than 360° carries an adjustable stop 3 (Figure 2) by 40 which the amplitude of the oscillations of the stop-disc can be regulated. An integral stop 4 is also formed on the disc 1 and is adapted to impact upon the buffer 5 fixed on a stationary part of the machine. On 45 the rotation of the stop-disc 1 the stop 3 strikes the lever 6 which by means of transmission gear hereinafter described actuates a dog clutch 7 to connect the cam shaft 19 with the driving shaft 14. The rotation of 50 the shaft 19 causes an outlet 22 to be opened by means of the cam 15, and, following upon the closure of the said outlet, opens the inlet 16^a by means of the cam 16. Between these 55 two operations the cam 8 acts upon the lever 9 (Figure 2) bearing on the end of the bolt

24, and thereby disengages the stop-disc 1 from the friction clutch 25 (Figure 2) whereupon the stop disc, is rotated in a clockwise direction by the spring 11 till the stop 4 impacts upon the buffer 5. On 60 further rotation of the cam 8 the lever 9 will be released and the clutch 25 reinserted by the pressure of the spring 10.

The disc 1 receives its movement from the gear wheel 26 which is driven by means of the axle 12 from the driving shaft 14 which in turn is in gear with the axle 27 driven by the shaft 28 of the drum 29.

The cam 21 (Figures 1 and 4) before the end of each partial rotation of the cam shaft 19 (in the course of each period) strikes the part 30 of the clutch lever 6 and brings the same into the starting position again, that is, with the dog clutch 7 out of engagement. Reconnection of the dog clutch occurs with successive periods.

The treatment of barley on a periodical shelling machine of this type takes seven or more times longer than the simple shelling of corn, and the course of the stop-disc 80 ought therefore to be shorter with corn shelling. Accordingly dual transmission gear 13 is arranged on the shaft 14. This shaft drives a friction clutch from which the stop disc 1 receives its motion so that with corn shelling the speed of rotation of the stop-disc can be made greater than in the case of the longer treatment of barley and in this manner a better regulation of the corn shelling is obtained.

The dual transmission gear 13 on the shaft 12 by which the gear wheel 26 is driven permits either slow or quick rotation of the shaft 12 through engagement with one or other of the tooth wheels on the axle 14 95 (Figure 1) and a greater amplitude of the stop disc 1 can be used for corn shelling.

Between the periodical outlet and inlet of the corn or grain a certain period of time elapses during which the machine runs without a load, that is, very little power is required for driving during this period and since the gearing of the machine is without automatic regulation of its speed there is an increase in the speed of the water motor or other power unit used and in the speed of the transmission gear and shelling machine.

In order to prevent this racing or rise in speed a proportionally dimensioned flywheel is arranged on the axle 17, whereby,

in known manner, a substantially constant speed of rotation is ensured, notwithstanding the varying load on the engine.

A fly-wheel 18 which at the same time 5 serves as an impeller for the fan of the machine is fixed on the axle 17 (Figs. 1 and 3). It is obvious that the fly-wheel can be arranged on the axle 17 independently of the impeller of the fan.

10 The stop-disc 1 can also be provided with one stop only, in which case its buffer on the stationary part of the machine is arranged so as to be adjustable and with this arrangement the stop of the stop-disc when the latter rotates in one direction will strike the lever 6 and when the disc rotates in the other direction will strike the adjustable buffer.

In Figure 4 a stop disc is shown of which the stop 4 impacts on the clutch lever 6 when 20 the disc is rotated in one direction and when the disc is rotated in the other direction impacts upon the buffer 5, which latter is adjustably disposed on the ring 39 of a stationary part of the machine so that by adjustment of the buffer 5 the amplitude of 25 the stop-disc can be regulated.

Having now fully described my invention what I claim and desire to secure by Letters Patent is:—

30 1. For machines for material treatment, feeding and discharging apparatus comprising an inlet and an outlet for the material, a cam shaft, cams on the said shaft adapted to open and close the said inlet and outlet, a driving shaft, a dog clutch slidable on and 35 rotatable with the cam shaft and adapted to connect the cam and driving shafts, a bent arm lever pivotally mounted and connected with the dog clutch, an axle, a stop disc loosely mounted on said axle, a friction 40 clutch positively driven from the driving shaft and normally in engagement with the said stop disc, a stop adjustable around the said disc and adapted to strike the said bent 45 arm lever to engage the dog clutch means for periodically disengaging the said stop disc and friction clutch, a spring acting on the stop disc in a direction opposite to the drive of the said friction clutch, a stop fixed 50 on the said stop disc, a buffer on a fixed part of the machine against which the said fixed stop impacts, and means for periodically disengaging the cam and driving shafts.

55 2. For machines for material treatment, feeding and discharging apparatus comprising an inlet and an outlet for the material, a cam shaft, cams on the said shaft adapted to open and close the said inlet and outlet, a driving shaft, a dog clutch slidable on and 60 rotatable with the cam shaft and adapted to

connect the cam and driving shafts, a bent arm lever connected with the dog clutch, an axle, a stop disc loosely mounted on said axle, a friction clutch normally in engagement with the said stop disc, variable transmission gear between the said friction clutch and the driving shaft, a stop adjustable around the said disc and adapted to strike the said bent arm lever to engage the dog clutch a cam on the driving shaft, a rocking 70 lever one end of which rests on the said cam, a spring pressed bolt which is connected for axial movement with the said stop disc and of which one end is in contact with the said pivotal lever, a spring acting on the stop 75 disc in a direction opposite to the drive of the said friction clutch, a stop fixed on the said stop disc, a buffer on a fixed part of the machine against which the said fixed stop impacts, and a second cam on the driving 80 shaft adapted to press periodically on one arm of the pivotal bent arm lever to disconnect the cam and driving shafts.

3. For machines for material treatment, feeding and discharging apparatus comprising an inlet and an outlet for the material, a cam shaft, cams on the said shaft adapted to open and close the said inlet and outlet, a driving shaft, a dog clutch slidable on and 85 rotatable with the cam shaft and adapted to connect the cam and driving shafts, a bent arm lever connected with the dog clutch, a stop disc loosely mounted on an axle, a friction clutch normally in engagement with the said stop disc, variable transmission gear between the said friction clutch and the driving shaft, a stop adjustable around the said disc and adapted to strike the said pivotal bent arm lever to cause the dog clutch to connect the cam and driving 90 shafts, a cam on the driving shaft, a rocking lever one end of which rests on the said cam, a spring pressed bolt which is connected for axial movement with the said stop disc and of which one end is in contact with the said 95 rocking lever, a spring acting on the stop disc in a direction opposite to the drive of the said friction clutch, a stop fixed on the said stop disc, a buffer on a fixed part of the machine against which the said fixed stop impacts, a second cam on the driving shaft adapted to press periodically on one arm of the pivotal bent arm lever to disconnect the cam and driving shafts, means for rotating 100 said driving shaft, gearing connecting the said means with the driving shaft, and a flywheel driven from said means.

In testimony whereof I affix my signature.

JOSEF PROKOP.
